AIR CIRCULATING DEVICE

David A. Martin, 4872 Wembley Place,
Beaverton, Oreg. 97005

Filed Oct. 25, 1974, Ser. No. 517,911

Term of patent 14 years

Int. Cl. D23—04

U.S. Cl. D23—160

FIG. 1 is an elevational view of an air circulating device showing my new design;

FIG. 2 is a top plan view thereof;

FIG. 3 is a bottom plan view thereof; and

FIG. 4 is an enlarged, fragmentary, elevational view of the lower portion of my air circulating device.

I claim:

The ornamental design for an air circulating device, as shown and described.
